CLAIM

The ornamental design for a wheel, as shown and described.

DESCRIPTION

FIG. 1 is a perspective view of a wheel showing our new design;

FIG. 2 is a front elevational view thereof; the rear elevational view is a mirror image of the front elevational view; and,

FIG. 3 is a right side elevational view thereof; the left side elevational view, the top plan view and the bottom plan view are similar to the right side elevational view.
